MEANS FOR LOOSENING OR TIGHTENING
CLOSURES

Louis Palmeri, Wethersfield, Conn.

Application December 23, 1935, Serial No. 55,789

1 Claim. (Cl. 215—46)

This invention relates to means for loosening or tightening closures such as the covers of jars or other containers.

It is well known that, particularly on fruit jars or the like, on which the closure is screwed on, it is often very difficult to turn said closure to tighten or open the same.

The object of this invention is to provide, as hereinafter described, means of this character which will be strong, durable, and simple in construction, and efficient in the use thereof as well as economical to produce.

My invention is illustrated in the accompanying drawing in which:

15 Figure 1 is a plan view, in elevation, of a jar closure comprising my invention.

Figure 2 is a side view in elevation thereof.

Figure 3 is a similar plan view illustrating one form of a tool, included in my invention, as applied to said closure for actuating the same.

Figure 4 is a side view in elevation thereof.

As shown in the drawing, my invention is illustrated in connection with a jar closure of common form comprising a sheet metal body 5 having a screw thread 6 formed thereon, and a sealing flange 7 extending from the front edge of said closure.

The object of my invention is accomplished by providing engageable means on said closure, and 30 a tool to be used in connection therewith as follows:

The said closure is provided with a boss 8 on the top thereof and a peripheral groove 9 in said cover adjacent the said top. The said boss may 35 be constructed in any suitable manner, such as by forming the same integrally with the closure or forming the said boss separately and securing it thereto.

The said tool comprises a ring shaped portion 40 10 having a boss engaging portion 11. This tool

may be constructed of wire which is twisted together to provide a handle portion 12 that may be secured in a handle 13.

In the form shown, the said tool is formed of a single length of wire twisted, as above described, and shaped to provide a boss receiving recess 14. 5

It will be noted that the boss engaging member, or a portion thereof, extends parallel to the ring portion and above the plane of said ring.

In the use of my invention, the tool is placed 10 so that the boss engaging member thereon will rest on the top of the closure with the boss within the recess 14. When the tool is in said position, the ring portion thereof will register with the groove 9 in the closure so that, when force is applied to said tool, to either tighten the said closure on the jar or loosen the same to open said jar, the said boss engaging portion will be slid into engagement with the boss and the ring portion will engage the groove 9, thereby retaining 15 the tool firmly in engagement with the closure 20 during the operation thereof.

It will be understood from the above description that, in addition to providing means for tightening or loosening the closure, I have also provided means for retaining the above described 25 tool securely in engagement therewith so that it cannot slip off from the said closure while force is applied thereto.

I claim:

In combination with a closure having a peripheral groove in the side and a single boss extending from the top thereof; a tool having, as an integral part thereof, a ring shaped portion adapted to engage said groove, and a boss engaging portion on a plane with the top of said cover and extending inwardly from said ring portion in position to engage said boss at two sides thereof. 35

LOUIS PALMERI.
